DESIGN FOR A BOTTLE OPENER

Fred O. Labich, Evanston, Ill.

Application November 29, 1945, Serial No. 124,177

Term of patent 14 years

(Cl. D44—29)

To all whom it may concern:

Be it known that I, Fred O. Labich, a citizen of the United States, residing at Evanston, county of Cook, and State of Illinois, have invented a new, original, and ornamental Design for a Bottle Opener, of which the following is a specification, reference being had to the accompanying drawing, forming a part thereof, in which:

Figure 1 is a top plan view of a bottle opener showing my new design; Fig. 2, a front elevational view; and Fig. 3, a side view in elevation of my new design.

I claim:

The ornamental design for a bottle opener, as shown.

FRED O. LABICH.
